W. S. MYERS.
CENTRIFUGAL CASTING MACHINE.
APPLICATION FILED NOV. 1, 1918.

Patented Sept. 5, 1922.

UNITED STATES PATENT OFFICE.

WALTER S. MYERS, OF DARBY, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL CASTING MACHINE.

Application filed November 1, 1918. Serial No. 260,645.

To all whom it may concern:

Be it known that I, WALTER S. MYERS, a citizen of the United States of America, and a resident of Darby, in the county of Delaware, in the State of Pennsylvania, have invented certain new and useful Improvements in Centrifugal Casting Machines, of which the following is a true and exact description, reference being had to the accompanying drawing, which forms part thereof.

My present invention relates to centrifugal pipe casting machines for forming relatively large size cast iron pipes; and the general object of the invention is to provide improved means for supporting the rotating mold during the casting operation and for connecting and disconnecting the mold from the mold rotating means and for moving the molds into and out of the casting machine.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of my invention.

Of the drawings:

Figure 1 is an elevation partly in section on the line 1—1 of Fig. 2.

Figure 2 is an end elevation of the apparatus shown in Figure 1.

Figure 3 is a sectional elevation of a portion of the apparatus shown in Figure 1, but on a larger scale than Figure 1, and Figure 4 is a view taken similarly to Figure 1, showing a modified construction.

In the drawings, and referring first to the construction shown in Figs. 1, 2 and 3, A represents the stationary supporting frame work of the casting machine proper and B represents a pedestal mounted thereon and rotatably supporting a member C to which one end member F of the rotating mold is secured in the casting oper-

ation. As shown, the member C is in the form of a sleeve having annular ball race members C' secured to its periphery as by shrinking them in place. Cooperating stationary ball race members B' are secured in the cylindrical seat B³ formed in the pedestal B as by means of the flange B² detachably closing one end of this seat. The opposite end of the seat B³ is closed by an integral inwardly projecting flange portion of the pedestal. Cooperating with each pair of ball races B' and C' are a set of bearing balls D. At one end of the rotatable sleeve C is formed a conical surface C² engaging the surface F' provided at the end of the mold. As shown, this engaging surface F' is formed on an end member F fitting against and separable from the spigot end of the body portion E of the rotating mold. The opposite end of the mold body is provided with a separable end member K which is formed with a conical socket to receive the end of a longitudinally movable driving spindle I. The latter is splined in an elongated tubular member H, which is journalled at its ends by ball bearings D^A mounted in the pedestals G and G^A mounted in the framework A. A driving pulley H', secured on the sleeve H, between the pedestals G and G^A, forms a means for imparting rotating power to the member H to rotate through the spindle I the rotatable mold E. To prevent slippage between the mold and the spindle I the latter is provided with a radial driving pin I³ to engage with a driving lug K² formed on the end member K. To axially advance the spindle I, I have provided a fluid pressure motor cylinder J which is in axial alignment with the spindle I and has its piston rod J' swivelled to the end of the spindle, as shown best in Fig. 3. To reduce friction in operation I preferably employ a ball thrust bearing J² between the spindle I and piston rod J' as shown. The mold E is provided with a dry sand lining E' and the end member F of the spigot end of the mold is provided with a seat for a dry sand collar F², while the end member K at the bell end of the

2
mold is provided with a seat for a suitably shaped collar K' formed of dried sand, or the like. In practice the end members F and K will ordinarily be detachably secured 5 to the ends of the mold body E as by means of clamping bolts to facilitate the proper assemblage and taking apart of the apparatus.

Mounted below the rotating mold and 10 approximately midway between the ends of the latter is a vertically acting fluid pressure motor cylinder M, the piston of which supports a cross head or cradle M' which forms a means for elevating the mold into and 15 out of its operative position in which it is in axial alignment with the spindle I and sleeve C. Stationary track rails L, extending transversely to the length of the mold below the latter, form a track along 20 which an empty mold may be rolled into position above the lowered cradle M', and along which a mold with the casting formed therein, lowered by the cradle upon the rails, may be rolled away for delivery to 25 the apparatus for pulling the casting out of the mold and for relining the latter preparatory to a subsequent molding operation. The molten casting forming metal may be introduced into the mold in any 30 known or suitable manner. O indicates the cast pipe in the mold.

In the modified construction shown in Fig. 4 the end member K^A of the mold engaged by the spindle I is at the spigot end 35 of the mold, and is provided with an annular recess seat for a dried sand core K¹⁰ against which the metal forming the spigot end of the pipe mold abuts. The end member F^A at the bell end of the mold is provided 40 with a seat for a suitably shaped dried sand core F¹⁰, and the end member F^A is formed with a central aperture through 45 which the mold may be charged with molten metal by any suitable or usual means not shown. In this form of my invention the mold is formed at the bell end with a portion externally tapered to fit in the tapered socket C¹⁰ formed in the rotatable annular member C^A, which is 50 journaled by means of ball bearings in the pedestal B^A. The arrangement shown in Fig. 4 permits of a more compact construction for the means supporting the end of the rotating mold remote from the axially 55 and rotatively movable spindle I, and permits of a reduction in the weight supported by the spindle I. The mold receiving cradle M¹⁰ carried by the piston or cylinder M in Fig. 4 is provided with rolls 60 M¹¹ directly engaged by the mold. These rolls facilitate the axial movement of the mold on the cradle necessary to engage and disengage the mold from the bearing member B^A.

With the casting apparatus shown it will 65 be obvious that a mold in condition for casting may be easily and expeditiously moved off of the supporting track rails L into operative relation with the means for supporting and rotating the mold in the casting operation, and that at the conclusion of 70 the casting operation the mold with the casting therein may be easily and quickly removed from the rotating means and taken away to the stations for withdrawing the 75 casting and putting the mold again in condition for a subsequent casting operation. As rapidly as the casting is formed in one mold and the latter is removed a previously prepared mold may be put in place so that a 80 large number of pipes may be cast in a given time in a single casting machine.

While in accordance with the provisions of the statutes I have illustrated and described the best form of my invention now 85 known to me it will be apparent to those skilled in the art that changes may be made in the form of the apparatus disclosed without departing from the spirit of my invention as set forth in the appended claims, 90 and that certain features of my invention may be used to advantage in certain cases without a corresponding use of other features.

Having now described my invention, what 95 I claim as new and desire to secure by Letters Patent, is:

1. In a centrifugal casting machine the combination of a rotatable element having a cone shaped portion adapted to engage 100 and center one end of a rotatable mold, a second rotatable element also having a cone shaped portion adapted to engage and center the other end of the mold, one of said rotating elements being formed with a central opening through which molten metal 105 can be charged into the mold, a means for adjusting one of said elements axially so as to grip and release the mold.

2. In a centrifugal casting machine the 110 combination with rotatable elements adapted to engage the opposite ends of a pipe mold, means for adjusting said elements toward and away from one another to grip and release a mold inserted between them, 115 supports along which a mold may be moved toward and away from said rotatable elements and mechanism for raising and lowering a mold from said supports into alignment with said mechanism.

3. In a centrifugal casting machine the combination with rotatable elements adapted to engage the opposite ends of a pipe 125 mold, means for adjusting said elements toward and away from one another to grip and release a mold inserted between them, tracks along which a mold may be moved toward and away from said elements and

mechanism for raising and lowering a mold from said tracks into alignment with said elements.

4. In a centrifugal casting machine, a mold or flask for forming pipe or columnar form articles comprising an elongated shell, head and tail core rings constituting

closures for the shell, and a support for the ends of the mold or flask, the core rings and supports having matching beveled portions to cause a lifting of the mold when the beveled portions are brought into engagement.

WALTER S. MYERS.
